UNITED STATES PATENT OFFICE.

WILLIAM H. PAYNE, OF PHILADELPHIA, PENNSYLVANIA, ASSIGNOR, BY
MESNE ASSIGNMENTS, TO ADELINE E. HOSKINS, OF SAME PLACE.

POCKET POWDER-PUFF AND INHALER DEVICE.

SPECIFICATION forming part of Letters Patent No. 478,358, dated July 5, 1892.

Application filed February 16, 1892. Serial No. 421,722. (No model.)

To all whom it may concern:

Be it known that I, WILLIAM H. PAYNE, a citizen of the United States, residing at the city of Philadelphia, in the county of Philadelphia and State of Pennsylvania, have invented certain new and useful Improvements in Pocket Powder-Puffs and Inhaling Devices, of which the following is a specification.

10 The principal object of my present invention is to provide a compact, neat, and comparatively inexpensive article or device adapted for use both as a smelling-bottle or inhaler and as a powder receptacle and puff and of 15 such general construction and arrangement as to permit of the closing up of the same when not in use, so as to be carried either in the hand or in the pocket.

My invention consists of the improvements 20 hereinafter described and claimed.

The general characteristic features of my invention will be more fully understood from the following description, taken in connection with the accompanying drawings, forming part hereof, and in which—

Figure 1 is an elevation of a pocket device or article embodying features of my invention and showing the parts thereof arranged in closed position for permitting the device to be 30 carried in the hand or in the pocket. Fig. 2 is a central section of Fig. 1, showing the construction and arrangement of the internal parts of the device. Fig. 3 is an elevation showing the device arranged for use as a powder-box and puff, and Fig. 4 is a similar view showing the device arranged for use as a smelling-tube or inhaling device.

In the drawings, *a* is the body portion of the pocket device or article. This body *a* is 40 preferably cylindrical in form and is provided with an expanded extremity *a'*, a contracted extremity *a''*, and a transversely-ranging partition *a³* intermediate of the respective extremities. This partition *a³* divides the interior of the body *a* into two compartments *b* and *c* for a purpose to be presently described.

d is a powder-puff comprising a socket *d'*, adapted for the reception of a pad or puff *d''* and provided with an acorn or other preferred 50 form of handle *d³*. The expanded portion *a'* of the body *a* is adapted for the reception of

the puff or pad *d''*, and the extremity of this expanded portion is provided with a lip *b'*, which engages with the cheeks *d⁴* of the powder-puff *d* and forms a tight joint, so that the 55 powder-puff *d* is detachably connected with the expanded extremity of the body *a* and is adapted to tightly close the open end of the compartment *b*.

e is a nozzle fitted into the contracted extremity *a''* of the body *a* and provided with a perforated diaphragm *e'*, which serves to retain a mass of sponge or other absorbent material *e²* to place in the compartment *c*.

c' are a series of radial apertures formed 65 in the contracted portion *a''* of the body *a* and communicating with the interior of the compartment *c*, so that the latter and its accessories constitute an effective smelling-tube or inhaling device.

f is a detachable cap adapted to be fitted onto and over the contracted extremity *a''* of the body *a*, in order to close the apertures *c'* and cover the nozzle *e*.

In use the chamber *b* is partially filled with 75 powder, and the sponge or other absorbent material *e²* is saturated with a suitable mixture. If preferred, the sponge *e²* may be dispensed with and smelling-salts may be introduced into the chamber *b* by removing the 80 nozzle *e*. The device may be used as a powder-puff by permitting the cap *f* to close the contracted end *a''* of the body *a*, Fig. 3, and then using the powder-puff *d*, in connection with the supply of powder in the chamber *b*, 85 in the usual or in any other preferred manner, and the device may be used as an inhaling device or smelling-tube by returning the powder-puff *d* to its normal position in the chamber *b* and then removing the cap *f*, Fig. 90 4, in order to permit of the application of the nozzle *f* to the nostrils in the usual or in any other preferred manner, it being understood that the apertures *c'* serve to admit air, which, after traversing the contents of the chamber 95 *c*, is inhaled by the user. Moreover, the perforated diaphragm *e'* serves to retain the contents of the chamber *c*, without in any wise interfering with the operation of the inhaling device or smelling-tube.

By fitting the cap *f* and puff *d* to place in 100 the respective extremities of the body *a*, Fig.

1, the device may be safely carried in the hand or in the pocket.

Having thus described the nature and objects of my invention, what I claim as new, and 5 desire to secure by Letters Patent, is—

A combined pocket powder-puff and smelling-tube or inhaler comprising a body portion expanded at one extremity and contracted at the other extremity and provided 10 with a transversely-ranging partition intermediate of the respective extremities, a socket provided with a handle and a powder puff or pad and adapted for insertion into said ex-

panded extremity, a nozzle adapted for insertion into said contracted extremity, and a detachable cap adapted to be fitted over said nozzle and onto said contracted extremity, substantially as and for the purposes set forth. 15

In witness whereof I have hereunto set my signature in the presence of two subscribing 20 witnesses:

WILLIAM H. PAYNE.

Witnesses:

GEORGE W. CLEMENT,
C. P. HOSKINS.
